UNITED STATES PATENT OFFICE.

BRYAN P. JOYCE, OF DAVENPORT, IOWA.

TRAIL FOR GUN CARRIAGES.

Application filed September 6, 1923. Serial No. 661,265.

(FILED UNDER THE ACT OF MARCH 3, 1883, 22 STAT. L., 625.)

To all whom it may concern:

Be it known that I, BRYAN P. JOYCE, a citizen of the United States, and a resident of Davenport, county of Scott, and State of Iowa, have invented an Improvement in Trails for Gun Carriages, of which the following is a specification.

The invention described herein may be used by the Government, or any of its officers or employees in prosecution of work for the Government, or by any other person in the United States, without payment to me of any royalty thereon, in accordance with the act of March 3, 1883.

15 The present invention relates to trails for gun carriages provided with detachable spades.

In certain types of gun carriages it has been found advisable to provide the trail 20 with a spade which in transport is detached from the trail so that the trail may be readily locked upon the limber.

The primary object of my invention then 25 is to provide means for detachably locking the spade to the trail.

Another object is the provision of means which in use is readily adapted at will to lock either the spade in position on the trail or the trail in position on the limber.

30 With the foregoing and other objects in view my invention resides in the novel arrangement and combination of parts and in the details of construction hereinafter described and claimed, it being understood 35 that changes in the precise embodiment of the invention herein disclosed may be made within the scope of what is claimed without departing from the spirit of the invention.

Other and further objects of this 40 invention will be obvious as the invention proceeds.

A practical embodiment of the invention is illustrated in the accompanying drawing, wherein:

45 Fig. 1 is a view in vertical section through the trail showing in side elevation the locking means therefor; and

Fig. 2 is a view in transverse section through the locking means.

50 Referring to the drawings by numerals of reference:

I have shown a trail "A" having a chamber or recess 1 provided with vertical walls 2 and an upper wall 3. At the lower

ends of the vertical walls are formed ledges 55 or projections 4 for a purpose hereinafter to be described. The same type of locking means is employed in locking the trail either to the spade or to the limber. In the preferred embodiment of my invention I have 60 shown the spade or limber B provided with a locking member C which is attached to the spade or limber by means of bolts or rivets and which passes up into the chamber or recess in the trail to lock the trail on the 65 spade or limber.

This locking member C is provided with side walls 5 and a top wall 6. Slidably mounted between the side walls 5 and guided thereby are a pair of plates 7 and 8 70 provided with slots 9 and 10. Rotatably mounted in the spade or limber and passing through these slots 9 and 10 and a corresponding slot 11 provided in the upper wall 75 of the chamber 1 of the trail is a lock actuating member 12. A bearing 13 for the actuating member is screw threaded as at 14 in the top of the locking member C.

The plates 7 and 8 are provided at their outer ends with beveled portions 15 and 16 80 cooperating with correspondingly beveled portions on the projections or lugs 4. At their inner ends the plates 7 and 8 are rabbeted so as to overlap. The actuating member 12 intermediate its ends and at the 85 point where it passes through the slots 9 and 10 is provided with oppositely faced cams movable in said slots and operating to reciprocate the slides 7 and 8. By turning the actuating member through an angle 90 of 180° it is obvious that the slides may be moved to or retracted from locking position with the projections or ledges 4 so as to firmly lock the trail upon the spade or limber or to release the same. 95

Any suitable locking means may be provided in order to secure the actuating member and consequently the slides in either locked or unlocked position. I have found in practice that the locking means described hereinafter is suitable for this purpose, though it is obvious that any other known type of locking means might as readily be employed. 100

At the point where the actuating member 105 passes through the opening 11 in the upper wall 3 of the chamber 1 of the trail it is provided with a serrated collar 20. Mount-

ed upon the upper wall of the chamber 1 and at one side of the opening 11 is a housing 21 in which is mounted for reciprocable movement a plunger 22 having a head 23 to engage the serrations in the collar 20 of the actuating member. A spring 24 mounted in the housing 21 presses at opposite ends against the head 23 and a nut 25 screw threaded in the housing 21 so as to constantly urge the plunger 22 into locking engagement with the collar 20. If desired, the plunger may be provided with a nut 26 for convenience in withdrawing the plunger from its locking position.

15 Inasmuch as considerable effort may be required to move the cams of the actuating member from locked to unlocked position it has been found expedient in practice to provide the actuating member with some means 20 such as the hexagonal head 27 for assisting in turning the cams. A wrench or like instrument may be used with said head.

While I have shown the chamber 1 provided with ledges or projections 4 it is obvious that suitable recesses or other means may be employed to cooperate with the beveled edges of the plates 7 and 8, without change of function.

In order to provide for the transmission 30 of the horizontal component of the firing load from the trail to the spade the vertical face of the front ledge or projection 28 abuts against the front edge 29 of the locking member C.

35 It is apparent that the locking member described is capable of use either for attaching the spade to the trail or when the spade has been detached from the trail for attaching the trail to the limber in traveling position of the gun.

I claim:

1. A gun trail provided with a recess forming a chamber, a locking member projecting into said chamber, plates slidably mounted on said locking member, slots in said plates and an actuating member passing through said slots and provided with oppositely directed cams adapted to operate therein, projections on the side walls of said chamber adapted to cooperate with said

plates, serrations on said actuating member and a spring pressed plunger mounted on said trail and provided with a head adapted to cooperate with said serrations to lock said actuating member in any adjusted position. 55

2. A gun trail provided with a recess forming a chamber, a locking member projecting into said chamber, plates slidably mounted on said locking member, slots in said plates, an actuating member passing 60 through said slots and provided with oppositely directed cams adapted to operate therein, means on the side walls of said chamber adapted to cooperate with said plates and means to lock the actuating member in any adjusted position. 65

3. A gun trail provided with a recess forming a chamber, a locking member projecting into said chamber, plates slidably mounted in said locking member, slots intermediate the ends of said plates, an actuating member passing through said slots and adapted to actuate said plates for reciprocable movement and means on said trail 70 adapted to cooperate with said plates to 75 lock the trail in position.

4. A gun trail provided with a recess forming a chamber, a locking member projecting into said chamber, slides on said locking member, cam means adapted to actuate said slides for reciprocable movement and means on the side walls of said chamber adapted to cooperate with said slides for locking the trail in position. 80

5. A gun trail provided with a recess 85 forming a chamber, a locking member projecting into said recess, slides on said locking member, projections on the inner walls of said chamber, means on said slides to cooperate with said projections and means 90 to actuate said slides for reciprocable movement.

6. A gun trail provided with a recess, a locking member projecting into said recess, slides on said locking member, means on said 95 trail adapted to cooperate with said slides for locking the locking member to said trail and means to actuate said slides for reciprocable movement.

BRYAN P. JOYCE.
